UNITED STATES PATENT OFFICE.

WILLIAM A. CURLEY, CLIFFORD SEAGER, AND ANDREW C. LA BEAUME, OF POPLAR BLUFF, MISSOURI.

LOCOMOTIVE SANDER.

Application filed July 19, 1926. Serial No. 123,375.

This invention is a novel improvement in locomotive sanding devices and the principal object of the invention is to provide a pair of novel devices adapted to be connected with the two side outlets of the usual sand dome of a locomotive at each side of the locomotive, and each device having plurality of sand leads, operated by individual air nozzles, connected therewith, the leads respectively conducting the sand to the track adjacent one of the driving wheels of the locomotive.

Another object of the device is to provide a pair of novel sand columns, adapted when attached to the sand dome, to fit closely to the side of the boiler casing of the locomotive and to lie substantially tangent thereto, whereby the heat of radiation from the boiler of the locomotive will always maintain the sand in a dry state in the sand columns and sand leads, and thus prevent caking of the sand within the sand columns and leads. A still further object is to provide a sand column having a relatively large opening at its top registering with the opening in the bottom portion of the sand dome of the locomotive, whereby the sand from the dome will fall freely into the sand column and maintain the latter filled with sand. A still further object is to provide a sand column having a flange at its upper end disposed at an angle to the axis of the column, so that when the flange is bolted to the side of the sand dome, the column will lie substantially tangent to the boiler casing of the locomotive.

We will explain the invention with reference to the accompanying drawings which illustrate one practical embodiment thereof to enable others familiar with the art to adopt and use the same and will summarize in the claims the novel features of construction, and novel combinations of parts, for which protection is desired.

In said drawings:

Fig. 1 is a transverse sectional view through a locomotive boiler adjacent the sand dome showing our improved sanding devices and piping connected therewith.

Fig. 2 is a side elevation of a portion of a locomotive showing our novel sand column and air piping connected with the sand dome.

Fig. 3 is an enlarged longitudinal detail section through the device.

Fig. 4 is a longitudinal section on the line 4—4, Fig. 3.

Fig. 5 is a transverse section on the line 5—5, Fig. 3.

As shown in drawings, the sanding device preferably comprises a tubular sand column 1, preferably a casting of suitable length and diameter, the lower end of the sand column 1, being internally threaded as at 1^a to receive a removable plug 2, adapted to be screwed into the lower end of the column 1, whereby the plug may be removed to permit access to the interior of the column. The upper end of sand column 1 is provided with a flange 1^b preferably formed integral with the column 1 and disposed at an angle to the longitudinal axis of the column 1, the angle preferably being about 30°, whereby when the flange is bolted to the sand dome D with the opening in the top of the sand column registering with the outlet in the bottom of the sand dome, as shown in Figs. 1 and 2, the sand column 1 will lie substantially tangent to the boiler casing of the locomotive, whereby the heat of radiation of the boiler will always maintain the sand within the column in a dry state. The flange 1^b is perforated, as shown, to receive the bolts or other means for fastening the flange to sand dome D.

Extending substantially radially from sand column 1, are a plurality of sand leads 3, 4 and 5—said leads all lying preferably in the same plane, but having their longitudinal axes slanting slightly upwardly toward the inlet or upper end of the sand column 1, as shown in Figs. 2 and 3 to prevent the sand from normally discharging from the sand leads hereinafter described, by gravitation. The sand leads each preferably comprise a short length of pipe of suitable diameter, having their inner ends screwed into outlet orifices 1^c in the side of the sand column 1 as shown in the drawing. The orifices 1^c are substantially spaced equal distances apart, the upper orifice being disposed on the right hand side of the sand column, (Figs. 2 and 3), and the two lower orifices being disposed on the left hand side of the column, as viewed in said figures.

At the outer ends of leads 3, 4 and 5 are heads 3^a, 4^a and 5^a respectively, said heads comprising tubular members screwed onto the outer ends of leads 3, 4 and 5, said

heads having plugs 3^b, 4^b and 5^b in the outer ends respectively, whereby access may be had to the interior of the sand leads 3, 4 and 5. Heads 3^a, 4^a and 5^a are furthermore provided with angularly disposed branches 3^c, 4^c and 5^c respectively which are preferably internally threaded as shown and adapted to be connected to the sand pipes, 6, 7 and 8 respectively, which discharge sand on the track adjacent the driving wheels of the locomotive. Branches 3^c, 4^c and 5^c are preferably disposed at angles of about 45° to the longitudinal axes of the heads.

In the heads diametrically opposite to and substantially in line with the sand pipe branches are perforated lugs 3^d, 4^d and 5^d respectively, which are preferably threaded to receive the blowout air piping herein-after described, which assists in discharging sand from the sand column and leads down through the pipes 6, 7 and 8 respectively.

Air nozzles are provided for each sand lead 3, 4 and 5, each nozzle comprising a short nozzle 1^d, extending through the casing 1 at a point substantially tangent to the interior diameter of the sand column and in line with the axis of its respective sand lead 3, 4 or 5, said nozzle having its outer end bent into alignment with the axes of its respective sand lead, as shown particularly in Fig 5, the nozzle 1^d being disposed substantially at right angles to the axis of its respective lead 3, 4, or 5. The casing 1 adjacent each nozzle 1^d is preferably enlarged and provided with an internally threaded bore 1^e, communicating with the nozzle 1^d, said threaded bore 1^e being adapted to receive the usual air plug 1^f attached to the end of the main air pipe feeding the nozzle. Each plug 1^f is preferably provided on its inner end with a plate 1^g having angularly disposed openings 1^h therein through which the air freely passes to the nozzle 1^d while preventing sand from passing from the nozzle and back into the air line past the plate 1^g.

As shown in Fig. 2 the blowout lug 4^d is directly connected to an air pipe 9 leading from a suitable source of air supply, the pipe 9 being controlled by a valve preferably operated in the cab of the locomotive.

Blowout lugs 3^d and 5^d are both connected to an air pipe 10 which is likewise preferably valved, the valve being operated in the cab of the locomotive, whereby air may be passed through either blowout pipes 9 or 10 separately or simultaneously, as desired.

The nozzle 1^d for the sand lead 4 is connected to a main air pipe 11, controlled by a valve situated in the locomotive cab and operated in the same manner as the valves controlling air pipes 9 and 10. The air nozzles for sand leads 3 and 5 are both con-

nected to an air pipe 12 similarly controlled by a valve in the cab of the locomotive.

The sand pipes 6 and 8 are arranged to discharge sand on the track immediately in front of the two front driving wheels of the locomotive, while the sand pipe 7 is arranged to discharge sand on the track immediately in the rear of the rear driving wheel of the locomotive. Hence, when it is desired to sand the track when the locomotive is moving, or about to move, in the forward direction the valve passing air through air pipe 12 to the nozzles of sand leads 3 and 5 alone would be operated. If desired to sand the track when the locomotive is moving, or about to move, in the reverse direction, the valve passing air through air pipe 11 to the nozzle of sand lead 4 alone would be operated, the nozzles for sand leads 3 and 5 being arranged to operate simultaneously, and the nozzle for sand lead 4 being arranged to operate independently of the nozzles for leads 3 and 5.

If sand should become caked or clogged in the heads 3^a and 5^a the valve of pipe 10 may be opened permitting a blast of air to blow out and clear the heads 3^a and 5^a. Similarly if head 4^a should become caked or clogged with wet sand, then the valve of pipe 9 may be opened admitting a blast of air through lug 4^d to clean out the head 4^a. If desired the valves of pipes 10 and 12 or 9 and 11 may be opened simultaneously to produce a maximum air blast not only in the column 1 but in the heads of the sand leads.

By placing the column 1 in the position shown in the drawing, the heat radiating from the boiler casing will maintain the sand in the columns dry and hot at all times, and thus prevent or largely eliminate caking of the sand in the columns or leads.

While we have shown three sand leads extending from each sand column, any number of leads may be applied thereto according to the requirements of the particular locomotive. The large opening in the top of the column registering with the opening in the lower portion of the sand dome will permit the sand column to be filled with sand from the dome at all times.

We do not limit our invention to the exact form shown in the drawings for obviously changes may be made therein within the scope of the claims.

We claim:

1. A sander for a locomotive having a sand dome; comprising a casing provided with a plurality of sand outlet orifices; sand leads connected with said orifices and having their axes slanting slightly upwardly; air nozzles extending into the casing opposite said outlet orifices; and said casing having a coupling flange at its upper end lying in a plane at an angle to the longitudinal axis of the casing, whereby when the casing is attached to the sand dome of a locomotive the

casing will lie substantially tangent to the locomotive boiler casing.

2. In a sander as set forth in claim 1, one set of sand leads discharging in front of the locomotive driving wheels and the other set discharging in rear of the driving wheels; and piping connecting each set of nozzles to operate each set independently of the other.

3. A sander for a locomotive having a sand dome; comprising a tubular casing provided with a plurality of sand outlet orifices, sand leads connected with said orifices and having their axes slanting slightly upwardly; air nozzles extending into the casing at right angles to and opposite each outlet orifice; and said casing having a coupling flange at its upper end lying in a plane at an angle to

the longitudinal axis of the casing whereby when the casing is attached to the sand dome of a locomotive the casing will lie substantially tangent to the locomotive boiler casing. 20

4. In a sander as set forth in claim 3, one set of sand leads discharging in front of the locomotive driving wheels and the other set discharging in rear of the driving wheels; 25 and valved piping connecting each set of nozzles to operate each set independently of the other.

In testimony that we claim the foregoing as our own we affix our signatures.

WILLIAM A. CURLEY.
